Des. 238,414

Patented Jan. 13, 1976

238,414

THERMOSTATIC CONTROL UNIT

John W. Stearley, Indiana, Pa., assignor to Robertshaw
Controls Company, Richmond, Va.

Filed July 22, 1974, Ser. No. 490,699

Term of patent 14 years

Int. Cl. D10—04

U.S. Cl. D10—50

FIG. 1

FIG. 3

FIG. 2

FIG. 4

FIG. 5

FIG. 1 is a left front perspective view of a thermostatic control unit showing my new design;

FIG. 2 is a front elevational view thereof, the rear not shown being substantially plain and unornamented;

FIG. 3 is a left side elevational view thereof, the right side being a mirror image thereto;

FIG. 4 is a top plan view thereof;

FIG. 5 is a bottom plan view thereof; and

FIG. 6 is an exploded front perspective view thereof.

I claim:

The ornamental design for a thermostatic control unit, as shown and described.
